UNITED STATES PATENT OFFICE.

ANDREW BRYSON, JR., AND HENRY S. MUDGE, OF BROOKLYN, NEW YORK.

AUTOMATIC GATE-LOCK FOR PNEUMATIC DISPATCH-TUBES.

SPECIFICATION forming part of Letters Patent No. 357,174, dated February 8, 1887.

Application filed September 23, 1886. Serial No. 214,363. (No model.)

To all whom it may concern:

Be it known that we, ANDREW BRYSON, Jr., and HENRY S. MUDGE, citizens of the United States, residing at Brooklyn, in the county of Kings, State of New York, have invented certain new and useful Improvements in Automatic Gate-Locks for Pneumatic Dispatch-Tubes, of which the following is a specification, reference being had therein to the accompanying drawings.

Our invention consists of a gate-locking mechanism by which a carrier is sent from a side station into the main way, the blocks and signals working automatically, and collisions rendered impossible, while right of way is always given to the main line.

Our invention is especially designed for use in pneumatic systems where high speed and heavy carriers necessitate the keeping of the main line open, although we do not limit it to such use.

Our gate-lock consists, essentially, of tables or blocks in the main line, connected by suitable mechanism with a gate at the way or branch station in such wise that a carrier passing over the tables in the main line automatically locks and unlocks the gate at the way or branch station at the moment of its passage, and thus maintains its right of way over a carrier about to leave the way-station and prevents collision.

In the accompanying drawings, which illustrate our invention, Figure 1 is a plan view of the main tube and branch; Fig. 2, a longitudinal section on line *x x* of Fig. 1; Fig. 3, a cross-section on line *y y* of Fig. 1, and Fig. 4 is an enlarged view of part of the mechanism shown in Fig. 2.

The direction of the air-current is shown by the arrow in Fig. 1.

A is the main, and *B* the branch line.

a a' are plates, secured at their rear to the way and having their free forward ends supported by standards *j j'*. Standard *j*, passing through the bottom of the tube, is fastened to one arm of lever *g*, so as to have a certain freedom of motion, in order that it may adjust itself to the lever-arm and the free end of plate *a* in its rise and fall, while at the same time offering a firm support for the latter. Standard *j'* also passes through the bottom of the tube

and has the same freedom of motion as standard *j*. It rests upon a coiled spring, *k*, which is sustained by a plate, *l*, suspended by screws *m* and nuts *n* from sleeve *h*, which is supported by one arm of lever *g*. Standard *j'* plays freely through sleeve *h* and a central aperture in plate *l*, and is only sustained by resting on spring *k*, which is of sufficient strength to lift the standard with plate *a'* when there is no carrier upon it. A bearing, *q*, in sleeve *h*, passing through slot *q'* in standard *j'*, serves to support and limit the play of the standard. It will be seen that by this arrangement a carrier passing over plate *a* will depress its end of lever *g* while raising the other arm of the lever, and with it sleeve *h* and standard *j'* and plate *a'*. Now, supposing two carriers in the main way to be so close together that both plates are covered at the same time, the carrier on plate *a'* will compress spring *k* upon plate *l* without carrying down sleeve *h*.

b is the gate, having an arm, *c*, and revolving with shaft *b'*. Gate *b* has a notch, *b''*, which locks with a chuck, *d*, on the end of an arm projecting from sleeve *h*, when sleeve *h* is raised by the upward movement of its end of lever *g* and gate *b* is in the closed position.

After the passage of a carrier onto the main way, which can only occur when gate *b* is unlocked, the gate is instantly closed by the action of spring *e*, attached to the gate and to arm *f*; or it may be actuated either by a coiled spring placed at the top or bottom of the tube. Shaft *b'* of gate *b* extends somewhat below the standard in which its lower end is pivoted and in which it has free play, so that both gate and shaft are able to rise and fall vertically as well as to revolve laterally. It follows that if the gate be open at the instant of the rise of chuck *d*, the latter will not engage with the notch in the gate, but, striking against its base, will lift both gate and shaft vertically, and thus relieve any undue strain on arm *h* of chuck *d*. A spring, *s*, coiled around shaft *b'* between its two bearings, has its lower end attached to the shaft and its upper end free, so that when the gate and shaft are lifted the spring is compressed against the upper bearing, and when the chuck falls assists in bringing the gate too down into place again.

A carrier passing over plate *a* in the main

line depresses the plate, and with it its arm of lever *g*. This raises the other arm of lever *g*, and with it sleeve *h* and chuck *d*, into engagement with gate *b*, which is thus locked in the closed position. The carrier on leaving *a* and passing over *a'*, which has been lifted by the up movement of sleeve *h*, depresses *a'*, and with it sleeve *h*, unlocking gate *b*, and at the same time raising plate *a* into its normal position.

10 If at the time of the passage of the carrier over plate *a'* a second carrier should be occupying plate *a*, plate *a'* will be depressed against the stress of spring *k* without moving sleeve *h*, and gate *b* will remain locked until the passage of the second and last carrier over plate *a'* frees plate *a* and allows the unlocking mechanism to operate.

15 It is evident that plates *a* and *a'*, by the use of parallel motion or other levers, may be made as long as may be required.

We do not limit the use of our invention to pneumatic dispatch systems only, as it is capable of ready application in any system where it is desired to secure a right of way to carriers over a main line without blockage or collision with those passing over branch lines.

Having thus described our invention, what we claim as new, and desire to secure by Letters Patent, is—

30 1. The combination of a table, a gate, a locking device, and suitable connecting mechanism whereby the gate is automatically locked by the movement of the table.

2. The combination of a table, a gate, an unlocking device, and suitable connecting mechanism whereby the gate is automatically unlocked by the movement of the table.

35 3. The combination of a gate, a device for locking and unlocking, a table for locking, a table for unlocking, and suitable mechanism between the tables and the locking and unlocking device whereby the gate is automatically locked and again unlocked by the successive movements of the respective tables.

40 45 4. The combination of a gate, a locking device, a table for locking, a table for unlocking, suitable connecting mechanisms between the

tables and the locking device, and connecting mechanism between the tables whereby the operation of the locking is not impeded by the simultaneous movement of both tables.

5. The combination of a gate, a locking and unlocking device, a table for locking, a table for unlocking, suitable connecting mechanism between the tables and the lock, and means for automatically returning the gate into a position in which the locking and unlocking mechanism becomes operative.

6. The combination of lever *g*, plate *a'*, standard *j'*, sleeve *h*, plate *l*, suspended from sleeve *h*, and spring *k*, substantially as and for the purposes described.

7. The combination of plate *a*, standard *j*, lever *g*, plate *a'*, standard *j'*, sleeve *h*, plate *l*, suspended from sleeve *h*, and spring *k*, substantially as and for the purposes described.

8. The combination, with lever *g*, of sleeve *h*, chuck *d*, and gate *b*, substantially as and for the purpose set forth.

9. The combination of plate *a*, standard *j*, lever *g*, sleeve *h*, chuck *d*, and gate *b*, substantially as and for the purpose set forth.

10. The combination of lever *g*, plate *a'*, standard *j'*, sleeve *h*, plate *l*, suspended from sleeve *h*, spring *k*, plate *a*, and standard *j*, substantially as and for the purpose set forth.

11. The combination, with lever *g*, of plate *a'*, standard *j'*, sleeve *h*, plate *l*, suspended from sleeve *h*, spring *k*, with gate *b* and chuck *d*, substantially as described.

12. The combination, with chuck *d*, of gate *b*, and shaft *b'*, capable of a vertical motion, substantially as and for the purpose hereinbefore set forth.

13. The combination, with chuck *d*, of gate *b*, shaft *b'*, and spring *s*, substantially as and for the purpose hereinbefore set forth.

In testimony whereof we affix our signatures in presence of two witnesses.

ANDREW BRYSON, JR.
HENRY S. MUDGE.
